UNITED STATES PATENT OFFICE.

WILLIAM H. PERRY, OF CONCORD, NEW HAMPSHIRE.

DESIGN FOR A MONUMENT.

SPECIFICATION forming part of Design No. 23,615, dated August 28, 1894.

Application filed August 1, 1894. Serial No. 519,217. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing.

My design consists essentially in the configuration of the shaft, its various ornamental tablets, and the different style of finish of the several parts, which will be fully set forth in the following specification and claim, and clearly illustrated in the accompanying drawing, on which figures and letters are used for reference.

The base 1, has four vertical sides terminating at their top in an obtuse frustum of a pyramid 2, upon which rests the pedestal having four vertical sides 3, which terminate at their top in an acute frustum of a pyramid 4, one or more sides of which is provided with a raised tablet 5.

The shaft has four tapering sides 6, ornamented with the polished tablets 7, and 8,—there being two of latter, one for each upper corner of either of the tapering sides, and all being distinguishable by heavy border lines

of the configuration shown at 9. The shaft is further ornamented with the raised tablets 30 10, and 11,—the former being at its bottom and having its upper edge beveled as seen at 12, the latter being at the top of the shaft and having its lower edge beveled, on all sides, as at 13,—the central portion of the beveled 35 edge 13, of each side being chamfered as at 14.

The corners of the tablet 11, are chamfered as seen at 15, and said tablet is further ornamented by a bead 16, cut in each of its vertical sides, and the top of said tablet terminates 40 in a pyramid, 17, in each side of which is formed a groove 18, tapering toward the top and having a convexed bottom as at 19. The several styles of finish for the different parts are designated by reference letters;—A, representing rock-work, B, hammered-work, and C, polished-work.

What I claim is—

The design for a monument, substantially as described and shown. 50

In testimony whereof I affix my signature in presence of two witnesses.

WILLIAM H. PERRY.
